ROTARY POSITIONING CONTROL APPARATUS

Eric Walter Paessler, Hackensack, N. J., assignor to Federal Telephone & Radio Corporation, New York, N. Y., a corporation of Delaware

Application December 29, 1942, Serial No. 470,468

6 Claims. (Cl. 74—10)

This invention relates to control apparatus and in particular to an apparatus for varying the reactance of a radio frequency oscillatory circuit so that it may be automatically tuned to a predetermined frequency.

Many control devices of this general type are to be found in the prior art and considerable development work in the past few years has been directed to their greater simplification and reliability as well as to reduction in size and decreased costs. The present invention is believed to be a distinct step forward in the attainment of these goals.

As above indicated one of the principal uses for this type of control apparatus is to rapidly vary the tuning of radio frequency circuits in either transmitters or receivers wherein it is desirable that any one of a number of predetermined frequencies be selected or changed from one value to another in a minimum of time. With the device of my invention the pressing of a momentary contact initiates a cycle of operation which in a few seconds will change the tuning of a radio circuit to any given predetermined frequency. If the requirements are such that more than one circuit is to be tuned, either a plurality of devices or one device operating on a plurality of circuits through suitable gearing may be employed.

Accordingly it is an object of my invention to devise a rugged control apparatus capable of tuning the circuits of radio apparatus to a predetermined frequency.

Another object of my invention is to devise an automatic means for resetting the control apparatus at the beginning of its operating sequences.

Another object of my invention is to devise a rotary positioning control apparatus whose sequences of operation may be initiated by a momentary contact push button.

Another object of my invention is to devise a control apparatus having a construction such that an operator may easily and readily adjust and reset the mechanism when it is necessary to change from one set of predetermined frequencies to another.

The features of the control apparatus of my invention lie primarily in its simplicity of construction and in its relatively small number of parts, as will be discerned as I proceed with the specification and description in connection with the accompanying drawings in which;

Fig. 1 represents in side elevation and in partial section a complete assembly view of an ex-

ample of control apparatus according to my invention;

Fig. 2 represents an elevation in section on line 2—2 in Fig. 1;

Fig. 3 represents an end elevation as seen from the line 3—3 in Fig. 1;

Fig. 4 is a plan view of the top of the Fig. 1 apparatus, showing the gear drive and clutch mechanism;

10 Figs. 5 and 6 are partial sectional views somewhat similar to that of Fig. 2, for the purpose of describing the operation of the control apparatus; and

Fig. 7 is a schematic diagram showing electrical circuits, cams, etc. employed in the automatic operation of the control apparatus.

Referring to Figs. 1 and 2, the end plates 1 and 2 of a frame structure are separated and also held together by three rectangular spacers 3, 4 and 5 and a tie-rod 6. The spacers and the tie-rod are more clearly shown in section in Fig. 2. The end plates 1 and 2 journal a control shaft or cam shaft 7. A variable tuning reactance (not shown), which may be either a variable capacitor, a variometer, or other variable element, is connected with control shaft 7 and rotated thereby to predetermined angular positions relative to a fixed radius of the shaft. It is the novel manner in which the rotation of shaft 7 is controlled by the operating mechanism which constitutes one of the principal features of my invention.

A spline or feathered key 8 extends along the control shaft or cam shaft 7 from a point beneath the spur gear 54 to the clamping nut 12. A plurality of spacers 9, each having a keyway for mating with the spline 8 are mounted on the shaft 7. Each spacer has a small shoulder 10 turned on one end thereof. Mounted between the spacers and on the shoulders 10 are selector cams 11, which under operating conditions are securely clamped in position between the nut 12 and the collar 13 the latter being secured to the shaft either by pinning or by a set-screw 14. The shaft 7 is held from axial displacement by collar 13 held fast to shaft 7 by set-screw 14' cooperating with collar 13 on the opposite side of plate 1. On the periphery of each selector cam is a notch 15. When adjusting the tuning device prior to operation, each notch 15 assumes a position corresponding to a predetermined frequency, as will be more fully explained hereinafter. When all of the selector cams are properly positioned with respect to their notches 15, they are securely clamped as stated above.

Also mounted between the end plates 1 and 2, is a reset shaft 16. On this reset shaft, in spaced relation, are mounted a plurality of members 17. Each member has three extensions or arms 18, 20 and 22, the arm 18 being designated a detent arm and having a projection or detent 19 extending from its outer end as shown. The shape of the detent corresponds to the shape of the notch 15 in the control cam. Both are slightly tapered or wedge shaped so that when in engagement no lost motion or backlash is permissible. The arm 20 is designated a latch arm and together with the latch 37 functions to control the operation of the mechanism, as will be hereinafter explained. The arm 22 is a spring arm and between a hole in this arm and a support 24 is a tension spring 23, Fig. 2. It will be noted that the support 24, spring 23, and several other elements have been removed from the apparatus shown in Fig. 1, in order to show the structure behind these elements.

Also supported on reset shaft 16 are a plurality of reset washers 25. The washers are formed with an integral internal projection or key 26 which extends into a key-way 27, the latter extending throughout the length of shaft 16. Each reset washer also has a bent-over portion 28 extending from its outer rim up and over the hub portion of the member 17. The members 17 and the reset washers 25 are maintained in spaced relation by the spacers 29. These members are not securely clamped together as is the case of the control cams, but are permitted to have a rotational slippage or free motion. The collar 30 at one end of the shaft 16 and the collar 31 at the other end of the shaft position the members 17 with respect to and in alignment with the control cams 11. The collar 31 is secured to the shaft by the set-screw 32. Lever 33, positioned on the shaft 16 between one of the reset washers 25 and the collar 30, has an integral internal key 26 extending within the keyway 27, and is employed for manually resetting the mechanism during periods when the apparatus is adjusted as a whole to operate at given predetermined frequencies.

Between the end plates 1 and 2 is a third shaft 34 on which are mounted a plurality of levers 35. Each member has oppositely extending arms 36 and 37 which in turn have bent-over portions 38 and 39 respectively. The portions 38 and 39 function as armatures for the electromagnets 48 and 49. An adjustable eccentric stop 39 determines the limit of rotation of the levers 35. This stop extends the whole distance between the end plates 1 and 2. The upper end 40 of the arm 37, together with the surface 41 of the arm 20 functions as a latching device, as will be hereinafter more fully described. The levers 35 are maintained in suitable spaced relation on the shaft 34 by spacers 42, collar 43 and collar 44, the latter being fastened to the shaft 34 by set-screw 45. The levers 35 also have a limited amount of free angular motion as is the case with the members 17 and the reset washers 25 on shaft 16.

The spacing members 4 and 5 have mounted thereon two L-shaped members 46 and 47 which act as supports for electromagnets 48 and 49. These electromagnets 48 and 49 are fastened to the L-shaped members 46 and 47 by passing their cores through slots in these members and riveting over. The L-shaped members are fastened to the supports 4 and 5 by means of screws 50 and 51. The electromagnets 48 and

49 are mounted in two groups of five each in order to conserve on space requirements. By so doing the total length of the mechanism can be nearly halved. It will be seen that each lever 35 contains two bent-over portions 38 and 39. The bent-over portion 38 on each of one set of alternate levers 35, serve as armatures for magnets 49, while the bent-over portions 39 on the other set of alternate levers 35 serve as armatures for magnets 48, there being only one magnet 48 or 49 cooperating with any single lever 35.

Referring now to Fig. 4, the spur gear 54, keyed to shaft 7 mates with spur gear 55, mounted on shaft 56, the latter also extending between and being journaled in the two end plates 1 and 2 of the supporting framework. Mounted on the shaft 56 and pinned or otherwise fastened thereto is a threaded sleeve 57. On one end of the sleeve is a clutch plate 58 having a hole in its center whereby it may move freely in an axial direction along the surface of the sleeve 57, the clutch plate 58 being splined to the sleeve 57 to prevent relative rotational motion therebetween. A compression spring 59 surrounding the sleeve 57 and held in position by the adjustable threaded collar 60, presses clutch plate 58 to the left in Fig. 4. A friction disc 61, made of cork for example, is positioned between the spur gear 55 and the clutch plate 58. The gear 55 is not keyed to the shaft 56 but is driven through the clutch mechanism as a result of friction and axial pressure exerted by spring 59. A spur gear 63 is also pinned or otherwise fastened, such as by set screw 64, to the shaft 56. Axial motion of the shaft 56 in either direction is prevented by the hub of the spur gear 63 and the collar 62, both of which are fast to shaft 56 and acting as retaining collars on either side of the end plate 1. Gear 63 is rotated by a motor (not shown) and serves as the driving gear for the complete mechanism. Its rotation causes the rotation of the shaft 56, the sleeve 57 and the clutch plate 58. The latter drives the gear 55 through the friction disc 61.

Mounted on the right hand side of the gear 63, Fig. 4, is a pivoted lever 65 which acts at the beginning of the operating cycle to reset or take out of engagement any detent 19 which may have been positioned in notch 15. In the position shown in Fig. 3, the spring 66, having one end supported by screw 67 fast to gear 63 and its other end passing through a hole in the upturned end 68 of the lever 65, holds the lever against a stop pin 69 mounted on gear 63. The lever is pivotally supported by gear 63 at the point 70.

On the shaft 16 is supported a lever 71 having two arms 72 and 73. Integral with lever 71 is a key 74 which fits into the keyway 27 of the shaft 16, so that any rotation of lever 71 rotates shaft 16. Arm 73 of the lever 71 is held against an adjustable eccentric stop 75 by a spring 76, one end of which passes through a hole in the arm 73 while the other end is held in fixed position by the screw 77. When the gear 63 rotates in the direction shown by the dotted arrow at the beginning of the cycle of operation, the upturned edge 78 of the lever 65 pushes the arm 72 of lever 71 in an upward or clockwise direction, Fig. 3, thus rotating shaft 16 and disengaging any detent 19 which may be positioned in notch 15, Fig. 2. As the rotation of gear 63 continues, the end 78 of lever 65 passes beyond the arm 72 and the latter is pulled back into its original position by the spring 76. During the latter part of the cycle operation, the gear 63 reverses its direction of rotation, as will be explained hereinafter, but this

motion has no effect on the lever 71, since the end 78 of lever 65 merely lifts over the end of the arm 72.

Fig. 7 is a schematic wiring diagram of electrical circuits which, in conjunction with a driving motor (not shown), relays, cams, etc., operates the control mechanism of my invention, so that it will finally come to rest at a predetermined position. In Fig. 7, the coils 101 and 102 represent two field windings of alternating current motor which may be rotated in one direction by energization of coil 101 and in a reverse direction by energization of coil 102. It will be understood that a suitable reversible direct current motor (not shown) may be used in place of the alternating current motor. Two cams 103 and 104 are driven by the motor through suitable reduction gearing not shown. A selector switch 105 selects for energization any one of the electromagnets 48 or 49 (see Fig. 2), depending upon the predetermined frequency to be selected. The mechanism, as illustrated and described, is suitable for determining any one of a total of ten frequencies. However, for simplification of the schematic wiring diagram, only one set of five electromagnets 48 have been shown connected with the five position selector switch 105 for selecting for operation the desired one of magnets 48. It will be understood, however, that any desired number of magnets 48 and 49, greater or less than ten, may be provided with a corresponding number of contacts in switch 105 for selecting the desired magnet for operation, each magnet 48 or 49 being employed to control the selection of a different predetermined frequency.

A cycle of operation will now be described. The position of all cams, relays, etc., of Fig. 7, are shown in the position they will acquire at the end of a cycle of operation or in other words when the driving motor is deenergized. When a new or different frequency is to be selected, the switch arm 106 of the selector switch is moved so as to make contact with a predetermined switch point 107 corresponding to the new frequency. The pressing of push button 108 closes two pair of contacts 109 and 110. The closing of contacts 109 completes a circuit from the positive terminal of battery 150 through contacts 109, contacts 111 on cam 103, conductor 112, winding of relay 113, conductor 114 to the negative terminal of battery 150, thereby energizing relay 113. The energization of this relay opens back contacts 115 and 116 and closes front contacts 117 and 118. The closing of contacts 117 completes a circuit from the A. C. power supply 151 through motor field winding 101, contact 117, conductor 119, conductor 120, contacts 118 (which are momentarily closed when push button 108 is depressed), conductor 121, conductor 122, back to the power source 151. The motor operates to drive cams 103 and 104 in the direction indicated by the arrows whereupon contacts 123 and 124 are closed by the raising of tongue 132 by cam 104. Contacts 123 being in parallel with contacts 110 permit the release of push button 108 without disrupting the power supply to the motor which continues to operate.

When relay 113 operates, it is locked by the closure of contacts 118 in parallel with contacts 109 over conductors 125 and 126. The motor advances cam 103 until the tongue 127 falls into slot 128. At this point contact 111 opens, thereby deenergizing the winding of relay 113. This results in the closure of contacts 115 and 116 and the opening of contacts 117 and 118, thereby re-

versing the direction of rotation of the motor and also the cams 103 and 104. The motor circuit is now traced from the A. C. power source 151, field winding 102, conductor 129, contacts 116, conductor 119, contacts 123, conductor 122 back to the power source 151. The closure of contacts 115 completes a circuit from the positive terminal of battery 150 through contacts 115, conductor 130, contacts 124, winding of selected magnet 48, contacts 107 and arm 106 of selector switch 105 back to battery 150. Cams 103 and 104 are now rotating in a direction opposite to that of the arrow shown thereon and continue to do so until tongue 132 falls into notch 133 of cam 104. At this point the motor is deenergized by the opening of contacts 123 and the winding of magnet 48 is deenergized by the opening of contact 124. This completes the cycle of control circuit operation.

During the cycle of electrical operations above described the following mechanical operations of the control mechanism take place. It is assumed that in the beginning of any cycle the various parts of the control mechanism are in a position such as is shown in Fig. 2. The detent 19 is within the notch 15 of one of the cams 11, thus fixing the angular position of reactance control shaft 7, corresponding to a certain predetermined frequency. When some other predetermined frequency is to be selected by the mechanism, the switch arm 106 is moved to the appropriate contact for the desired frequency and momentary contact 108 is depressed. As above stated this starts the driving motor. In addition to the cams 103 and 104 shown in Fig. 7 the gear 63 is also driven through suitable gearing by the driving motor. As the gear 63 rotates in the direction of the dotted arrow, as shown in Fig. 3, the cams 103 and 104 rotate in the direction of the full arrows as shown in Fig. 7. Gear 63 rotates shaft 56 to which the sleeve 57 is fastened. Clutch plate 58 which is splined to sleeve 57 is rotated by the latter. Spring 59 presses against clutch plate 58, which in turn forces the friction disc 61 against gear 55. This tends to rotate the gear 55, but at the beginning of an operating cycle this rotation cannot take place since gear 55 is in mesh with gear 54 and this latter gear is prevented from rotating by the detent 19 in notch 15. There is therefore a slippage of the clutch mechanism. However, gear 63 in its counter-clockwise rotation, Fig. 3, also rotates the lever 65 and the end 78 of this lever in pressing against arm 72 of lever 71, disengages the detent 19 from the notch 15. This disengaging is actually done by the bent-over portion 28 of the reset washers 25, the latter being also keyed to the shaft 16. When this occurs the latch arm 20 of the member 17 raises and the spring 52 rotates the latch 31 into the position shown in Fig. 5, wherein the end 40 of arm 31 engages surface 41 and prevents arm 20 from clockwise rotation, thus preventing detent 19 from latching into notch 15, none of the operating magnets 48 or 49 being energized at this time. The withdrawal of the detent 19 permits gear 54 and in turn all of the control cams to be operated through the clutch mechanism 58, 61, 55. The rotation of gear 54 continues until the tongue 127 drops into slot 128 of the cam 103; see Fig. 7. At this point the reversal of the driving motor takes place and gear 63 through the clutch mechanism 58, 61, 55, also reverses the rotation of gear 54. It is at this point that the winding 75 on the predetermined selector magnet is en-

ergized and the positions of the various parts become as shown in Fig. 6. As the control cam continues to rotate the notch 15 finally comes into position under the detent 19 and since the armature 38 or 39 as the case may be has been pulled up by the operating magnet, the arm 20 is free to rotate and the detent 19 falls into the notch 15, thus stopping the rotation of all cams 11 and the gear 54. A slippage of the clutch mechanism again takes place but the driving motor continues to rotate cams 103 and 104 until the tongue 132 falls into slot 133 at which time the cycle of operation is completed.

Let it now be assumed that one wishes to change the adjustment of one of the cams 11 so that the control apparatus will tune the radio apparatus to a different frequency. The nut 12 is loosened thereby relieving the pressure existing between all of the spacers 9 and the cams 11. In order not to disturb the adjustments of other cams, the nut 12 is loosened only when the detent 19 is in the notch 15 of the cam which is to be readjusted. After the nut has been loosened and the cams are free to rotate, a manual turning of the knob 80 which is also splined to the shaft 7 rotates all cams except the one which is held in position by its detent 19. The oscillatory circuit reactance which is controlled by the rotation of shaft 7 is varied by turning knob 80 until the desired new frequency is obtained. The nut 12 is again tightened and the apparatus is now in adjustment for the new frequency. It will be seen that the procedure for changing the frequency is of the utmost simplicity and is one of the features of the invention. In order to exert a certain amount of pressure between all spacers 9 and cams 11, when the nut 12 is loosened, a spring washer 81, located between the collar 82 and one of the cams 11, exerts sufficient pressure against the spacers and cams to prevent any slip-page which might otherwise accidentally occur.

The invention has been described primarily as a mechanism for automatically tuning radio frequency circuits to predetermined frequencies. It is obvious, however, that the apparatus of my invention could be used in any arrangement where a predetermined setting of any movable part is required and it is intended that the scope of my invention be not limited except in accordance with the following claims.

What is claimed is:

1. Rotary position determining means comprising an angularly movable cam shaft, a plurality of spacers splined on said shaft, a plurality of circular cams, each provided with a notch on its periphery, mounted on and between said spacers, means for clamping said cams between said spacers whereby said notches may be fixed at predetermined angular positions relative to a fixed radius of said shaft; a reset shaft, a plurality of members comprising detents and latch arms mounted on said reset shaft, each detent having an engaged and disengaged position with respect to a cooperating notch on one of said cams, a plurality of reset washers splined to said reset shaft and having means for disengaging said detents from said notches when said reset shaft is angularly moved; driving means, including a slipping clutch mechanism for rotating said cam shaft alternately in a forward direction and a reverse direction, reset control means operative in response to said forward rotation of said driving means momentarily angularly moving said reset shaft whereby all detents are

placed in said disengaged position, means for latching said detents in said disengaged position during said forward direction of rotation of said driving means, means for reversing said direction of rotation, and means for unlatching a predetermined one of said detents whereby said unlatched detent may move to the engaged position with its cooperating notch and stop the motion of said cam shaft.

5 10 15 20 25 30 35 40 45 50 55 60 65 70 75 80 85 90 95

2. Rotary position determining means comprising an angularly movable cam shaft, a plurality of spacers splined on said shaft, a plurality of circular cams, each provided with a notch on its periphery, mounted on and between said spacers, means for clamping said cams between said spacers whereby said notches may be fixed at predetermined angular positions relative to a fixed radius of said shaft; detent means having engaged and disengaged positions with respect to cooperating notches on said cams, driving means for rotating said cam shaft alternately in a forward direction and in a reverse direction, means for urging said detents to their disengaged positions at the start of said forward direction of rotation, means for latching said detents in their disengaged positions, means for reversing said direction of rotation, and means for unlatching a selected one of said detents whereby said unlatched detent may move to the engaged position with its cooperating notch and stop the motion of said cam shaft.

3. In a rotary position determining control apparatus, a rotary control shaft, a plurality of selector cams mounted on said control shaft, a reset shaft, a plurality of detents mounted on said reset shaft, said detents having an engaged and a disengaged position, means on the periphery of said selector cams for engaging with said detents at predetermined positions of said control shaft, reset means mounted on said reset shaft, latching means for maintaining said detents in their disengaged position during certain periods of operation of the control apparatus, means for releasing said latching means during certain other periods of operation of said apparatus, driving means for rotating said control shaft, and reset control means operative in response to said rotation of said driving means for momentarily angularly moving said reset shaft whereby all detents are placed in said disengaged position.

4. In rotary position determining control apparatus in accordance with claim 3, the combination in which said reset control means comprises a first lever pivotally mounted on said driving means and a second lever mounted on said reset shaft and in operative relationship with said first lever.

5. In rotary position determining control apparatus in accordance with claim 3, the combination in which said reset means mounted on said reset shaft comprises a plurality of reset washers, at least one of said washers having means for disengaging one of said detents in response to the operation of said reset control means.

6. In rotary position determining control apparatus in accordance with claim 3, in the combination in which said driving means include means for rotating said shaft alternately in a forward direction and in a reverse direction and said reset control means is responsive to said forward rotation.

ERIC WALTER PAESSLER.
